Primary Examiner — John R Yeh

Assistant Examiner — Dustin Andrew Griffith

(57) **CLAIM**

The ornamental design for a toy storage basket, as shown and described.

DESCRIPTION

FIG. 1 is a perspective view of a toy storage basket in an open state, showing our new design.

FIG. 2 is a front view of a toy storage basket.

FIG. 3 is a rear view of a toy storage basket.

FIG. 4 is a left side view of a toy storage basket.

FIG. 5 is a right side view of a toy storage basket.

FIG. 6 is a top view of a toy storage basket.

FIG. 7 is a bottom view of a toy storage basket; and,

FIG. 8 is a perspective view of a toy storage basket in a closed state.

The broken lines illustrate stitching lines and form part of the claimed design.

Any shading and cross-hatching are not features of the design but are utilized to illustrate the surface contours of the toy storage basket design in the drawings.

1 Claim, 8 Drawing Sheets
